attorney

UNITED STATES PATENT OFFICE.

WILLIAM WILLIAMS, OF MURRUMBEENA, VICTORIA, AUSTRALIA, ASSIGNOR OF ONE-SIXTH TO SAMUEL RICHARD FAIRCLOUGH, OF TOORAK, VICTORIA, AUSTRALIA.

LIFTING-JACK.

1,404,824.

Specification of Letters Patent. Patented Jan. 31, 1922.

Application filed September 10, 1920. Serial No. 409,413.

To all whom it may concern:

Be it known that I, WILLIAM WILLIAMS, a subject of the King of Great Britain and Ireland, etc., residing at Murrumbeena, in the State of Victoria, Commonwealth of Australia, have invented certain new and useful Improvements in Lifting-Jacks, for which I have filed an application in Australia, May 19, 1920, No. 15,730; and I do hereby declare the following to be a full, clear, and exact description of the invention, such as will enable others skilled in the art to which it appertains to make and use the same.

15 This invention relates to lifting jacks having a fixed and a lifting pillar, and whereby after each lifting stroke the lifting pillar locks itself in raised position. Means of adjustment are provided so that the lifting pillar head, or load supporting part, will begin its work at the height required, and the distance of lift of each stroke may be regulated.

20 The jack may be all metal, or partly wood, the latter being useful to form a fixed pillar base of considerable area but light weight; or metal extensions may be bolted on or be integral with the base of the fixed pillar. Integral with or bolted on the fixed pillar are guides for the lifting pillar to make the latter when moved rise or fall in a vertical plane or nearly so. Other parts of the construction will be explained by reference to the drawings herewith in which 25 the lifting jack is illustrated but the construction may be varied in designs, proportions and minor details of parts while retaining matter hereinafter claimed. The drawings are partly diagrammatic.

40 Figure 1 is a side view of the jack ready to lift a load.

Figure 2 is a side view of the jack showing the parts at the end of a lifting stroke.

45 Figure 3 is a plan of the jack in horizontal section on lines E, E through Figure 1 omitting the handle.

Figure 4 is a sectional view through the fixed and lifting pillars.

50 Figure 5 is a view of the outer end of the lever.

Figure 6 shows parts of my jack in dupli-

cate to explain how to lift a vehicle axle or like broad load by applying two jacks but using only one handle.

Figure 7 shows in side view part of the 55 lifting pillar modified, and adjacent parts.

Figure 8 is a sectional plan of part of Figure 7.

The fixed pillar 2 has a foot 1, and straps or loops 3, 4 which enclose and guide the 60 lifting pillar 10 during vertical movement of the latter.

Strap 4 has an eye 5 to hold the leg top 6 hereafter described. The lifting pillar has a slot or a series of slots 9 or a hole 9^a 65 or series of holes along its length, and has a wide top 10^a for load supporting purposes.

Hinged to one end 11 of head 10^a is a plate 12, on which the load can be supported, but plate 12 can be swung out of working position as indicated by the adjacent arrow in Figure 1, so as to allow the load to be lower, on top 10^a.

The under side of plate 12 has flanges 13, 13^a at opposite ends, to enclose the top 10^a 75 and to avoid danger of displacement of plate 12. Pillar 10 may have at its lower part a hook, eye, step, or the like for connection or support of the article to be lifted. A transverse bolt 10^b or the transverse part of 80 a member 10^c forming a pivot is engaged through a lifting pillar slot 9 or hole 9^a, and at each side of pillar 10 the bolt 10^b carries pivotally a link 10^d the other end of which is pivoted to a lever 14 which is recessed and is shown of looped form or U shape. In some cases instead of links 10^d the U shaped linking member shown in Figure 7 is used having arms or sides 10^e.

In the fixed pillar there is a hole for a 90 pivot bolt at 2^a, which also passes through the sides of lever 14. Lever 14 is fulcrumed by the pivot bolt at 2^a and at 14^a is pivoted to links 10^d or arms 10^e.

The lever can be depressed when the load 95 is moderate by pressure of an attendant's foot on its outer end 15, but for heavier loads the lever is to be grasped by a removable handle 16 which when attached forms a lever extension. For attachment purposes this 100 handle has, at one end, a series of slots 17, 18, 19 extending in different directions one

of which is to be engaged with the transverse end 15 of the lever. One of these slots extends obliquely to the handle length, another is about longitudinal with said length, 5 and another is about at right angles thereto. By utilizing a suitable slot the handle can be set to extend in a suitable position for operation, having in view the surrounding circumstances. The front bearing 5 encloses 10 the top 6 of leg 7 having at its base a foot 8 which extends forwardly when required as in Figures 1 to 3, to help to support the loaded jack.

This foot can be swung to the side of the 15 jack, or the leg can be raised a little and rotated to the rear when it is not required for supporting purposes.

In order to lift the whole of an axle and connected parts uniformly, or to lift a like 20 specially wide load, two jack bodies are used but only one handle 16.

Parts of two jacks are shown in Figure 6; the two levers 14 are spaced apart to the distance by adjustable framing consisting of 25 bent slide bars 14^b, 14^c one at each side, attached to the levers as by fitting on lugs 14^a, on the latter. The lugs 14^a are screw threaded, carrying nuts 21, the parts of 30 each jack not shown in Figure 6 being as in Figure 1. Collars 14^e on slide bars 14^b, 14^c hold them in adjusted position, and each collar may have a set screw.

When the (or each) lifting pillar is lowered, and loaded ready for lifting, the handle is engaged with lever 14 or with the cross framing in Figure 6. The handle will be operated to depress the outer end of the (or each) lever 14. This raises the movable pillar (or pillars) but towards the end of 40 the lever stroke the links 10^a (or the members 10^e) are swung so that their pivots 14^a at the end of each lever 14 pass their dead centres, as will be understood from Figure 2 or Figure 7 causing a slight fall of the lifting pillar resulting in pressure being applied to each lever 14 tending to swing its pivoted end as per arrow B. But at the time stated the outer end of each lever 14 bears against the fixed post 2 as in Figure 45 2 at 2^b, or a like stop so that the lever can move no farther, and the jack becomes locked against lowering of the raised load.

The detachable handle may be used at will to release each lever, and thus each lifting 50 pillar.

There may be one or more additional fulcrum holes in lever 14 as at 2^c so that the lever is made adjustable by shifting the fulcrum pin to vary the lever effect under the 60 application of power.

The handle outer end has a hook 20 which can be engaged under the base of end 15 of lever 14 when the latter is lowered, so that by pulling the handle the lever can be raised 65 to lower the lifting pillar.

The slots 9 are cut into that side of pillar 10 which is remote from pillar 2, pillar 10 having an unbroken edge alongside of the edge of pillar 2.

It is important that there shall be easy 70 detachment from the engaged slot of the part 10^b or 10^c set therein, and easy adjustment of such part in any other slot 9 so that the working height of the lifting pillar may be rapidly altered.

When there are several holes 9^a the alteration would take longer to effect and entail more trouble; the risk that the cross bolt 10^b might be misplaced is avoided by using the member having sides 10^c. The construction in Figures 7 and 8 allows the transverse members at 2^a and 10^c to be located in pillars having only small dimensions from the front C to the rear D.

Having described this invention, what is 85 claimed by Letters Patent is:—

1. In a lifting jack, a lifting pillar in front of a fixed pillar, a lever of U shape pivoted to the fixed pillar and linked to the lifting pillar, and a handle having a series 90 of end slots extending in different directions for engagement of a suitable slot with a transverse part of the lever.

2. In a lifting jack, a lifting pillar, a fixed pillar linked to the lifting pillar, 95 guide loops on the fixed pillar through which loops the lifting pillar passes, and a leg pivotally supported by one of said loops.

3. A lifting jack having a lifting pillar, the front edge of which contains a series of 100 slots, a fixed pillar behind the lifting pillar and having projecting loops by which the lifting pillar is kept in alignment, a recessed lever pivoted to the fixed pillar, and linking means engaged in one of the said slots 105 and pivoted to the lever, so that a stroke of the lever raises the lifting pillar and locks it in raised position.

4. In a lifting jack, a fixed pillar having an enlarged foot, and upper and lower forwardly projecting loops which guide and retain a lifting pillar in alignment, a socket on the lower loop, and an adjustable leg the top of which engages the socket.

5. In a lifting jack, the lifting pillar adjacent to a fixed pillar behind it, loops from the fixed pillar to guide the lifting pillar, an adjustable lever pivoted to the fixed pillar, adjustable linking means pivoted to the lever, slots in the lifting pillar front edge 115 in any of which the linking means is engageable, and an adjustable leg the top of which is socketed in front of the lifting pillar.

6. A lifting jack having the construction 125 in claim 6 combined with a handle which has at one end a series of slots extending in different directions, and at the other end a hook.

7. Lifting jacks of the kind described each 130

having a **U** shaped lever by which to lift and lock a lifting pillar in raised position, combined with transverse framing and a handle having slots in its end for the purpose set forth.

5 8. The combination of two lifting jacks of the construction stated in claim 3 spaced

apart by intermediate framing, and a handle to move the said framing to raise the lifting pillar of each jack. 10

In witness whereof I have hereunto set my hand.

WILLIAM WILLIAMS.
